UNITED STATES PATENT OFFICE.

ELDIA J. CARTER, ALBERT TAYLOR, AND JAMES S. GRIFFITH, OF MOBRIDGE, SOUTH DAKOTA.

SPARK-ARRESTER FOR LOCOMOTIVES.

1,243,708.

Specification of Letters Patent. Patented Oct. 23, 1917.

Application filed March 18, 1915, Serial No. 15,157. Renewed August 18, 1917. Serial No. 186,916.

To all whom it may concern:

Be it known that we, ELDIA J. CARTER, ALBERT TAYLOR, and JAMES S. GRIFFITH, citizens of the United States, residing at 5 Mobridge, in the county of Walworth and State of South Dakota, have invented certain new and useful Improvements in Spark Arresters for Locomotives; and we do hereby declare the following to be a full, clear, 10 and exact description of the invention, such as will enable others skilled in the art to which it appertains to make and use the same.

Our invention relates to locomotives and 15 has for its object to provide an improved spark arrester or destroyer therefor; and, generally stated, the invention consists of the novel devices and combinations of devices hereinafter described and defined in 20 the claims.

It is, of course, a well known fact that many fires are started along the right-of-way by sparks emitted from the smoke stacks of locomotives. Various spark ar- 25 resters have been provided for stopping or collecting the sparks within the smoke box of the locomotive, but such devices have hitherto been inefficient to stop all of the 30 sparks or have been subject to a serious defect, that they would interfere with the draft of the locomotive.

Our invention provides a spark arrester which does not interfere with the draft of the locomotive and the chief function of 35 which is to break up the red hot sparks into such fine form that they will almost instantly, either burn entirely up, or be cooled and extinguished, so that they will not start fires after they have been deposited along 40 the right-of-way.

The invention, in its preferred form, is illustrated in the accompanying drawings wherein like characters indicate like parts throughout the several views.

Referring to the drawings:

Figure 1 is a longitudinal section taken centrally through the smoke stack and a portion of the boiler of a locomotive, and illustrating our invention applied in connection 50 with the smoke stack and exhaust nozzle.

Fig. 2 is an enlarged vertical section taken approximately on the line x^2+x^2 on Fig. 1.

Fig. 3 is a section taken approximately on the line x^3+x^3 on Fig. 2; 55

Fig. 4 is a transverse vertical section taken on the line x^4+x^4 on Fig. 1;

Fig. 5 is a horizontal section taken on the line x^5+x^5 on Fig. 1; and

Fig. 6 is a horizontal section taken on the line x^6+x^6 on Fig. 1 looking upward.

Of the parts of the locomotive, the numeral 1 indicates the boiler, the numeral 2 the smoke box, the numeral 3 the flues, the numeral 4 the steam pipe, the numeral 5 the exhaust nozzle or exhaust nozzle stand, the numeral 6 the smoke stack and the numeral 7 the deflecting plate, all of which parts are of standard or well known construction.

In the application of our invention, the 70 lower section 6^a of the smoke stack is made or provided with a downwardly flaring conical lower end portion 6^b, and a conical plate or center cone 8 is suitably secured in a position concentric to the said flaring end 6^b, 75 and is preferably secured directly to the upper end of the exhaust nozzle 5, being, of course, provided with a passage through which the exhaust from the said nozzle may freely pass upward. As shown, the said cone 8 is attached to the nozzle by means of small angle brackets 9 and coöperating rivets or bolts, and preferably, the said cone is made up of several overlapped segments, which, at their outer edge portions are se- 85 cured together with freedom for circumferential expansion and contraction, by means of bolt and slot connections 10. The outer of the said bolts 10 are relatively long and reach from the sectional cone 8 to the 90 conical lower end 6^b of the stack, and are anchored to the said part 6^b so that they assist in properly spacing the said parts 8 and 6^b. The said cone 8 and conical lower end 6^b of the stack are thus spaced apart, 95 so that they afford a converging annular or conical smoke passage 11. The numeral 12 indicates so-called striking pins which are preferably of iron or steel and rectangular in cross section, and provided, each, at one 100 end, with a reduced threaded trunnion 13 on which is a pair of washers 14 and 15 and a clamping nut 16. A large number of these striking pins are provided and they are arranged in a multiplicity of circumferentially spaced rows, and they are secured to

the interior of the stack section 6^a, to its flaring lower end portion 6^b and to the cone or conical plate 8. Their trunnions 13 are passed through perforations in the said parts to which they are applied with the washers 14 and 15 clamping the said parts to which they are applied, when the said nuts 16 are tightened. It will be noted that the said striking pins are set so that they incline 5 slightly downward and radiate in respect to the axis of the stack. Here it should be noted that the striking pins 12 that are within the stack section 6^a terminate short of the axis of the stack far enough to leave 10 an unobstructed central or axial passage for the exhaust from the exhaust nozzle. The said striking pins of the several vertically spaced horizontal series are staggered in respect to each other, preferably as illustrated 15 in Fig. 2, so that the sparks passing upward between the same will strike in succession against the vertically spaced rows of pins. The striking pins that are applied to the conical portions 6^b and 8 are staggered in 20 respect to each other, so that the sparks which are drawn upward into the smoke stack, will be caused to strike over and over again against the said pins and will mostly be disintegrated and broken up before they 25 are carried into the stack proper. Thus, those reaching the stack will be further caused to strike against the pins in the lower stack section 6^a, so that by the time they have 30 passed out of the stack, they will be pulverized or broken up to such an extent that they will be either burned or cooled so that they will not start fires along the right-of-way. It is well known that when a coal or 35 spark is violently thrust against a hard surface, it will be split up into such fine particles that fire will be immediately put out, and where this does not happen, that the small broken particles will very quickly cool in passing through the air, and thus their 40 ability to start fires is destroyed. Some of the broken sparks or cinders may fall to the bottom of the smoke box, but these, of course, may be readily removed.

The numeral 17 indicates washout pipes 45 which extend from the boiler forward, through or slightly under the deflecting plate 7, and terminate at their front ends below the flaring lower end of the stack, so that the discharge therefrom will be effective to wash out the smoke box. The downward inclination of the striking pins toward the axis of the stack, has a tendency to cause the sparks to be deflected radially outward and to keep the same away from the 50 unobstructed axial exhaust passage of the stack.

The device described is efficient for the purposes had in view and may be readily applied, either to new or to old locomotives, 55 at comparatively small cost.

What we claim is:

1. The combination with a smoke box, smoke stack and exhaust nozzle of a locomotive, said smoke stack having a downwardly flaring lower end within said smoke 70 box and around the upper end of said exhaust nozzle, of a conical pin support surrounding the upper end of said exhaust nozzle and having an axial exhaust passage alined with that of the said nozzle, the said 75 conical pin support being spaced from the flaring lower end of said stack to form an upwardly converging annular smoke passage leading to the stack, and striking pins secured, at one end, to the said stack and to 80 said conical pin support, with their free ends projecting into the smoke passage, and the free ends of the pins on the interior of said stack terminating short of the axis thereof, so as to leave an unobstructed axial exhaust 85 passage from the said exhaust nozzle upward through the said stack.

2. The combination with a smoke box, smoke stack and exhaust nozzle of a locomotive, said smoke stack having a downwardly flaring lower end within said smoke 90 box and around the upper end of said exhaust nozzle, of a conical pin support surrounding the upper end of said exhaust nozzle and having an axial exhaust passage 95 alined with that of the said nozzle, the said conical pin support being spaced from the flaring lower end of said stack to form an upwardly converging annular smoke passage leading to the stack, and striking pins secured, at one end, to the said stack and to 100 said conical pin support, with their free ends projecting into the smoke passage, the free ends of the pins on the interior of said stack terminating short of the axis thereof, 105 so as to leave an unobstructed axial exhaust passage from the said exhaust nozzle upward through the said stack, and the pins on the body of the stack having an inward and downward incline so as to deflect the 110 sparks outward from the axis of the stack.

3. The combination with a smoke box, smoke stack and exhaust nozzle of a locomotive, said smoke stack having a downwardly flaring lower end within said smoke 115 box and around the upper end of said exhaust nozzle, of a conical pin support surrounding the upper end of said exhaust nozzle and having an axial exhaust passage alined with that of the said nozzle, the said 120 conical pin support being spaced from the flaring lower end of said stack to form an upwardly converging annular smoke passage leading to the stack, and striking pins secured, at one end, to the said stack and to 125 said conical pin support, with their free ends projecting into the smoke passage, and the free ends of the pins on the interior of said stack terminating short of the axis thereof, so as to leave an unobstructed axial exhaust 130

passage from the said exhaust nozzle upward through the said stack, all of that portion of the said stack which is above said smoke box being entirely free from obstructions.

- 5 4. The combination with a smoke box, smoke stack and exhaust nozzle of a locomotive, said smoke stack having a downwardly flaring lower end within said smoke box and around the upper end of said exhaust nozzle, of a conical pin support surrounding the upper end of said exhaust nozzle and having an axial exhaust passage alined with that of the said nozzle, the said conical pin support being spaced from the flaring lower end of said stack to form an upwardly converging annular smoke passage leading to the stack, and striking pins secured, at one end, to the said stack and to said conical pin support, with their free ends projecting into the smoke passage, and the free ends of the pins on the interior of said stack terminating short of the axis thereof, so as to leave an unobstructed axial exhaust passage from the said exhaust nozzle upward through said stack, and the striking pins on said conical pin support being staggered and interlapped with the striking pins on the flaring lower end of said stack.
- 10 5. The combination with a smoke box, smoke stack and exhaust nozzle of a locomotive, said smoke stack having a downwardly

flaring lower end within said smoke box and around the upper end of said exhaust nozzle, of a conical pin support surrounding the upper end of said exhaust nozzle and having an axial exhaust passage alined with that of the said nozzle, the said conical pin support being spaced from the flaring lower end of said stack to form an upwardly converging annular smoke passage leading to the stack, and striking pins secured, at one end, to the said stack and to said conical pin support, with their free ends projecting into the smoke passage, and the free ends of the pins on the interior of said stack terminating short of the axis thereof, so as to leave an unobstructed axial exhaust passage from the said exhaust nozzle upward through the said stack, and a deflecting plate on the flue sheet side of the smoke box extending forward and downward to a point below the said flaring lower end of the stack and the lower portion of said conical pin support.
